UNITED STATES PATENT OFFICE.

CORYDON I. BUSH, OF PORTSMOUTH, OHIO.

ATTACHMENT FOR HORSE-BRUSHES.

No. 857,268.

Specification of Letters Patent.

Patented June 18, 1907.

Application filed February 1, 1906. Serial No. 299,036.

To all whom it may concern:

Be it known that I, CORYDON I. BUSH, a citizen of the United States of America, residing at Portsmouth, in the county of 5 Scioto and State of Ohio, have invented certain new and useful Improvements in Attachments for Horse-Brushes, &c.; and I do hereby declare that the following is a full, clear, and exact description of the invention, such as will enable others to make and use the same, reference being had to the accompanying drawing, forming a part of this specification.

The principal object of the invention is, 15 to secure a horse brush, or similar device to the hand, so as to prevent its accidental withdrawal from the back strap and also relieve the fatigue occasioned by the grasp of the hand, so that the hand may be at liberty 20 and free to govern or change the position of the brush at will. Second, to increase or decrease the tension of the hand securing means.

The invention consists in the novel construction and combination of parts, such as 25 will be first fully described and then specifically pointed out in the claims.

In the drawings: Figure 1. is a view in perspective, of a horse brush, with the hand 30 shown in dotted lines and in position beneath the back strap and the novel hand securing devices upon the brush and back strap. Fig. 2. is a cross, sectional view of the back strap on the brush, taken through 35 the toothed plate and the clips securing said plate to the strap, also showing a portion of the pivoted tooth engaging bar, and—Fig. 3. is a view, in perspective, of a portion of the back strap, showing a modified form of the 40 toothed plate.

Similar letters of reference indicate corresponding parts in all the figures of the drawing.

Referring to the drawings, 5 indicates a 45 horse brush, of the usual description, it being composed of a back 6, oblate in form, and the fibrous portion 7. Connected with the longitudinal edge portions of the back 6, of the brush, is a wide back strap 8, the strap extending in the line of an arc of a circle above 50 the back 6, and beneath which the hand is extended in the use of the brush.

Upon the upper surface of the back strap, at a point intermediate the ends of the back 55 strap is the band holder, consisting of a curved strip or plate 9, arranged edgewise

in position, and which is in the shape of a horse shoe, the curved portion being adjacent to the rear edge of the back strap and the ends of the plate extended forwardly to 60 within a short distance of the forward edge of said strap. Between the ends of plate 9 is connected rigidly a transverse base plate 10. Upon the forward edge of plate 10 are the flexible clasping points or extensions 65 12, 12, which are bent downwardly and extended upon the under surface of the back strap 8. With the inner edge of plate 10, at a point equi-distant from the sides of the plate 9, is connected a pivot plate 14, which 70 is narrow in width and extends a considerable distance inwardly in the direction of the curved portion of said plate 9. With the upper edge of said curved portion of plate 9 is rigidly connected a narrow strip or plate 75 15, which extends a short distance inwardly, and in said plate is a horizontal slot 16.

Beneath the plate 15 is a detachable U shaped clamping plate for plate 9, one portion 17 of which extends vertically in direction and adjacent to the rear edge portion of the strap 8, and the other portions 18 and 19 extend at right angles thereto, the portion 18 bearing upon the under surface of the strap 8, and the other portion 19 bearing upon the 80 under surface of the plate 15. In the portion 19 of the plate is a screw threaded opening 20. In the slot 16, of plate 15, is inserted an adjusting clamping screw 21, which extends through the opening 20, in the plate 90 15, and bears upon the upper surface of the strap 8.

In the upper edge portion of the sides of plate 9 are a series of forwardly extended, curved teeth 22, which are spaced apart, having 95 between them the depressions 23.

24 indicates a band securing arm or bar, a short portion of which is bent downwardly and reduced in circumference and extended through the perforation 25, in the pivot 100 plate 14, the said reduced portion being upset upon the under surface of the said plate. The other end of the bar 24 extends a short distance beyond the outer surface of the plate 9 and a short portion of said end bent 105 in an upward direction to form a wrist, the bar resting normally in one of the depressions 23, in plate 9. Upon the said upwardly bent end of bar 9 is secured a disk 26, which forms a shoulder above the bend in said bar. 110

27 indicates the hand securing strap or band, one end of which is perforated and ex-

tends over the upwardly bent end of bar 24 and bears on the disk 26. A separate disk 28, is secured to said upwardly bent end of the bar 24 above the end of strap 27, which 5 prevents the accidental removal of the strap. The other end of strap 27 is extended to form a loop, so as to pass over the back of the hand past the joint of the thumb and to a position beneath the back strap 8, and is secured re- 10 movably to the upper surface of the back 6, by means of a screw 29, the said end portion of said strap being provided with a series of perforations 30, in line with each other.

In the employment of the brush the securing 15 bar 24, for strap 27 is moved in position so as to bring the upper end of strap 27 directly above the position of its lower end, which movement extends the loop and permits the hand to enter the loop and pass under the 20 strap 8, the thumb being as usual, bearing on the outer surface of the said strap. In this position of the hand the bar 24 is turned upon its pivot as far as required to enable the slack in the loop in the strap to be drawn inwardly, 25 and hold the hand, the bar passing readily over the curved teeth 22, and entering the proper depression 23, the brush being then fastened to the hand.

In the employment of the brush the fingers 30 not being required to grasp the back of the brush, bear upon the upper surface without fatigue, the positions of the brush being readily changed by the pressure of the fingers. In brushes with flexible backs the hand is 35 free to raise the brush to take a curved position.

Instead of the curved plate 9 in which the teeth are formed, a structure of slight cost 40 may be employed, as indicated in the modification in Fig. 3, in which 31 indicates a series of teeth formed from a single piece of wire. The teeth are made to correspond with the teeth 22, in Fig. 1, as to shape. The teeth are first formed in the wire intermediate 45 its ends, and then the series of teeth bent in a curved or U shape, and placed in position on the back strap, as in Fig. 1, the series of teeth 31, at the end of the series at the forward edge of the back strap being secured 50 rigidly to the upper surface and ends of a transverse plate 32, the intermediate portion of which is curved or arched upwardly and perforated at 33. The ends 34, of the wire from which the teeth 31 are formed are extended upon the under surface of the back 55 strap, thence upwardly past the rear edge of the back strap and secured to the portions of the wire teeth adjoining thereto.

The securing bar 35 is bent downwardly at 60 its inner end and a portion reduced in size extended within the perforations 33, in the transverse plate 32 and upset as in Fig. 1. The hand securing strap is secured to the outer end of the bar as described in Fig. 1.

65 The brush can be secured to either right or

left hand, the arm or bar 24 being moved in the half circuit from one side of plate 9, to the other.

In securing the fastening device to the back strap, the forward edge of the strap is 70 inserted in the bent extensions 12, of plate 10, and the clamping plate 17 extended over the rear edge of the strap and the upper angle portion 9, secured to the inwardly extended plate 15, by the adjusting screw 21. 75

The invention is applicable to the securing of the free ends of any band, so that the slack can be taken up and to implements other than horse brushes, and such modifications employed as are within the scope of 80 the invention.

Having fully described my invention, what I now claim as new and desire to secure by Letters Patent is:

1. In a brush attachment the combination 85 with the back strap a hand retaining band and a base plate on said back strap, an arm pivotally connected with the base plate with which the free end of the hand retaining band is connected, a fixed support for 90 the end of the hand retaining band opposite to that connected with said arm and locking devices for said arm on said base plate.

2. In a brush attachment the combination 95 with the back strap a hand retaining band, a base plate on said back strap an arm pivotally connected at one end with said base plate and a wrist upon the outer end of said arm with which the free end of the hand retaining band is connected, a fixed support for the end of said hand retaining band opposite to that connected with said arm and inclined teeth on said base plate engaged by said pivoted arm.

3. In a brush attachment the combination 105 with the back strap a hand retaining band, a base plate on the back strap, securing devices on the said base plate with which the free end of the hand retaining band is connected, a fixed support for the end of the 110 said hand retaining band opposite to that connected with the securing devices, and adjustable securing devices on the base plate.

4. A horse brush a back strap thereon, a hand retaining band connected at one end 115 with the back of the brush, and a band holding and taking up device, detachably connected with the back strap and with which the other end of the hand retaining band is connected.

5. In a brush attachment, the combination 120 with the back of the brush, a back strap, a hand retaining band secured at one end to the back of the brush, a plate on the back strap, an arm pivotally connected at one end with said plate and having the other end pivotally connected with the free end of the hand retaining band, and securing means for the arm connected with the said plate.

6. In a brush attachment, the combina- 130

tion with the back of the brush, a back strap, a hand retaining band secured at one end to the back of the brush, a plate on the back strap, an arm pivotally connected at one end 5 with the said plate and having the other end pivotally connected with the free end of the hand retaining band, and retaining devices for said arm connected with said plate.

7. In a brush attachment, the combination 10 with the back of the brush, a back strap, a hand retaining band detachably secured at one end to the back of the brush, a plate secured to the back strap, and an arm pivot-

ally connected at one end to said plate and having the other end pivotally connected 15 with the free end of the hand retaining band, a curved plate connected with the plate on the back of the strap, having toothed openings adapted to receive said arm, an inwardly extended plate on the upper edge of said 20 curved plate having a slot, a clamping plate on the back strap and an adjusting screw.

CORYDON I. BUSH.
